UNITED STATES PATENT OFFICE.

JOSEPH FRENCH, OF WOONSOCKET, RHODE ISLAND.

DETACHABLY-SECURED LABEL.

1,093,985.

Specification of Letters Patent. Patented Apr. 21, 1914.

Application filed June 1, 1908. Serial No. 436,011.

To all whom it may concern:

Be it known that I, JOSEPH FRENCH, a citizen of the United States, residing at Woonsocket, in the county of Providence, 5 State of Rhode Island, have invented a certain new and useful Improvement in Detachably-Secured Labels, of which the following is a specification, reference being had therein to the accompanying drawings.

10 The general object of the invention is to provide in convenient and practical manner for quickly attaching labels securely to articles of all classes, such as aforesaid, with ready detachability, and without the use of spurs 15 or other metallic fastenings, and without injury to the appearance or condition of such articles, however fine or delicate the latter may be, and also without liability to cause injury to the rolls of mangles or other machinery employed to operate upon the 20 articles thus labeled.

The gist of the invention consists in a label fastened temporarily to the desired article of apparel, etc., by a thread or 25 threads serving to securely hold the label to the article during the required treatment of the latter, but which may readily be unraveled or withdrawn, and removed, to permit the label to be detached at pleasure.

30 The invention may be carried into effect in various ways.

The invention is illustrated in the drawings, in which,—

Figure 1 is a face view of a portion of an 35 article of woven material having a label attached thereto in conformity with the invention. Fig. 2 is a back view thereof. Fig. 3 is a sectional detail on an enlarged scale. Figs. 4, 5, 6 and 7, respectively, are 40 views showing different ways in which labels may be applied.

The invention provides in novel manner for the attachment of labels for the purpose of temporary identification to articles of 45 apparel or other personal use, household linen, etc., about to undergo the operations of a laundry of a cleaning establishment, or other analogous treatment, and designed also for employment in connection with 50 manufacturing processes for attaching labels temporarily to articles of apparel or other articles of woven and knit goods, or of leather, or to parts of such articles. At the present time it is usual in laundries to mark

white or light-colored articles by writing or 55 printing thereon with ink, and shoe-linings and other parts of shoes in process of manufacture are printed or stamped in ink. Some use is made by laundries of labels consisting of pieces of white tape furnished 60 with metallic spurs, more especially in connection with articles which do not show or readily take markings in ink, such as dark pieces, stockings, etc., a label of this character being attached by forcing the spurs 65 through the material of an article and bending or clenching them at the back or inner side thereof. The required marking or imprint is effected upon the label, instead of 70 upon the article itself. The subsequent removal of the label is effected by straightening the spurs and withdrawing them from the article. But the application of ink to many articles of fine and delicate character is undesirable and not permissible, and they 75 would be injured by the spurs of the described labels. Hence the use of either of these means of identification in connection therewith is precluded. The use of labels attached by spurs or other metallic fastenings is precluded in the case, also, of articles 80 which have to pass the rolls of machines such as mangles, on account of the injury to the surfaces of such rolls that would be occasioned by the spurs or other fastenings 85 aforesaid, and by the means of uniting them to the tape.

Having reference to the drawings,—In each figure, the article of which a portion is shown is designated 1, the label is designated 90 2, and 3, 3^a, are removable attaching threads. The said threads are combined with each other and with the label and the article to which it is applied, so as to unite the former to the latter by means of stitches passing 95 through the said label and article. Premising that the number of stitches, as well as the number of threads and the particular mode in which the stitches are formed, may vary in different applications of the invention, it will be observed that in each of the instances shown in the drawings two threads are employed, the thread 3 being formed into loops 3^b, 3^c, Figs. 2 and 3, passing through the article and label from one side 100 of these latter to the other thereof, and the thread 3^a being extended through the said loops at the said other side, thus locking the 105

loops so as to prevent their withdrawal. These stitches are produced in practice by means of a two-thread lock-stitch sewing machine having the tensions of the respective threads so adjusted that one thread (3^a) is under relatively heavy tension and the other thread (3) under relatively slight tension. This adjustment of the tensions permits loops of thread 3 to be extended by 5 the taut thread 3^a through the article and label, thread 3^a remaining in straight condition at its side of the article and label. As thus combined, the threads hold the label to the article. For additional security, one or 10 more stitches may be made in the article at each side or end of the label, as shown, so that strain upon the label may not start the stitches and disconnect the label. Loose ends 3^c, 3^c, of the threads are left projecting 15 at both ends of the line of stitches, partly for the same reason, but chiefly to serve as pull-ends which may be grasped for the purpose of pulling out the threads.

When it is desired to detach the label, one 20 of the projecting ends of the thread 3^a is taken hold of and such thread is pulled lengthwise through the loops of thread 3, which is quickly and easily effected. Thread 25 and the label then are free to be removed. 30 The stitches shown in the drawings and described above may readily be produced by two-thread lock-stitch sewing machines of kinds at present in use.

It will be perceived that the gist of the 35 invention consists in securing labels temporarily to the required articles by stitches which are sufficiently firm to hold the labels attached during the handling or treatment of the articles, but which may be unraveled 40 at will by simply grasping pull-ends and drawing thereon, so as thereby to release the labels and permit the removal thereof.

In Figs. 1 and 3 of the drawings the label is shown attached by a line of stitches extending transversely across the same near one end thereof, leaving the other end and greater portion of the length of the label free. This facilitates the handling of the label in writing upon the same or presenting it to the printing devices of a marking machine. In Fig. 4 the label is doubled crosswise upon itself and its two ends are attached to the article by the line of stitches, so that the loop of the label projects from 50 the edge of the article like the pull-strap of a shoe. This arrangement of the label also facilitates the marking or printing of the same. In Fig. 5 the line of stitches extends lengthwise of the label. In Fig. 6, two lines 55 of stitches extend across the width of the label, one near each end thereof. In Fig. 7, a single line of stitches extends cross the label, at the middle of the length of the latter.

I usually employ a thread 3^a which, by 60 reason of the nature of its material, or the treatment to which it has been subjected, or its greater size, is less liable to yield and bend than the thread 3. This favors the straight position of the former thread in the 65 stitches, and enables this result to be attained with less difference in the tension of the two threads. This difference in flexibility may be secured variously as has just been indicated; herein, by way of illustration, I have shown thread 3^a a little coarser than thread 3. A coarse thread is easier to grasp and pull upon than a fine one.

To guide in selecting the proper thread to pull upon in raveling the stitches, the 70 threads 3, 3^a, are differentiated from each other in appearance. This is effected by making use of threads differing from each other in size, as in the present instance in the 75 drawings, or by the use of threads differing in color, as indicated also by the drawings, or otherwise in obvious manner.

To aid in finding the pull-thread 3^a, I employ for the same a thread of color and appearance most likely to contrast with those 80 of the article with which the invention is employed. For instance, I use a dark or black thread in the case of light-colored articles, and a yellow or red thread for dark goods.

I claim as my invention,—

1. The combination with an article substantially such as specified, and an identification label or the like, of a draw-thread engaging with the said label and with the said 100 article and securing the said label to the article with capacity for readily being detached by withdrawal of said thread.

2. The combination with an article substantially such as specified, and an identification label or the like, of threads engaging with each other and holding the label to the article and adapted to be readily unraveled and withdrawn to release the label.

3. The combination with an article, of a laundry marking consisting of a washable identification label or the like, and a thread formed into a plurality of loops passing through the article, and a second thread extending lengthwise through the said loops and adapted to be withdrawn lengthwise therethrough to release the label, whereby the label is detachably secured to the article.

4. The combination with an article, and an identification label or the like, of two threads interengaging in a plurality of stitches holding the label to the article, one thereof a draw-thread which is relatively less flexible than the other whereby it occupies in the 120 stitches a position facilitating its withdrawal, whereby the label is detachably secured to the article.

5. The combination with an article, and an

identification label or the like, of two threads interengaging in a plurality of stitches holding the label to the article, one thereof constituting a draw-thread and differentiated in 5 appearance from the other, to guide in unraveling the stitches, whereby the label is detachably secured to the article.

In testimony whereof I affix my signature in presence of two witnesses.

JOSEPH FRENCH.
